United States Patent Office.

GEORGE WILKINSON, OF PROVIDENCE, RHODE ISLAND, ASSIGNOR TO THE GORHAM MANUFACTURING COMPANY, OF SAME PLACE.

Design No. 2,994, dated April 7, 1868.

DESIGN FOR A FORK OR SPOON-HANDLE CALLED "DORIC."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver and other metals and plated ware, of which the following is a full, clear, and exact description, reference being had to the accompanying specimens or drawings, making part of this specification; that is to say, for a design called the "Doric" for the handles of spoons, forks, and other table-ware and implements, of which—

The said design consists of the general outline, shape, form, or contour of the handle, as represented, with ornamental configurations of a character suited thereto.

The said outline comprises a rounded or cylindrical stem or shaft, B, having a collar, n, near the bowl S, and expanding, by shoulders e e, into an oval shape, D, and this (oval) expanding by a neck, a, into an oval paddle-blade shape, G.

The ornamentation represented in the drawing, consists of a plain bevelled edge extending around the blade G and oval, D, to the shoulders e e, with a rosette or flower in the oval, D, and with a simple knot or tie, c, near the shoulders e e, and a knot and sprig of Grecian honeysuckle extending from the oval upon the blade G.

Claim.

I claim the design for the handles of spoons, forks, &c., as herein set forth and shown.

GEO. WILKINSON.
